UNITED STATES PATENT OFFICE.

NICHOLAS BENENATI, OF NEW YORK, N. Y.

MOUNTED GAS HEATER.

Application filed November 15, 1926. Serial No. 148,537.

This invention relates generally to mounted gas heaters and has special reference to apparel apparatus for use in connection with hat-cleaning and blocking establishments.

5 By way of introduction it may be pointed out that due to crowded urban conditions, the inevitable practice is to locate a hat-cleaning or blocking business along the busiest thoroughfares and due to the attending 10 high rentals prevailing for such a location, the establishment must, of necessity, be relatively small. In order to meet the requirements of such limited quarters, apparatus and machinery used in connection therewith, 15 has been designed to take up a small amount of floor space, but at the same time serve a variety of purposes.

The particular apparatus to which this invention is directed comprises a boiler embodying certain heat-producing means in the 20 form of gas burners, or the like, wherein a suitable quantity of steam is generated for use in connection with hat-cleaning or the like. Heretofore it has been the practice to 25 mount a gas plate upon the top of said boiler, said plate usually having separable heating means and supporting sad-irons or similar implements.

One of the forms for securing a gas plate 30 to a boiler comprises a plurality of brackets bolted or otherwise secured to depending legs of said plate, the whole emerging as a rigid structure more or less susceptible to the tremendous expansion and contraction 35 during the operation of said plate over the boiler. Obviously, the disadvantage of such a rigid mounting results in warped or cracked plates since no compensation is provided for the ever changing temperature of 40 the apparatus.

It is therefore the primary object of my 45 invention to provide means for attaching a gas plate to a boiler whereby the expansion and contraction thereof may be readily compensated.

A further object of the invention resides in the provision of means for supporting a burner on said plate sustaining means and position said burner below the latter.

50 A still further object is to provide a neat and attractive device, comprising but a few simple parts, readily assembled and disassembled without any special mechanical skill.

55 With these objects in view, together with others which will appear as the description

proceeds, the invention resides in the novel formation, combination, and arrangement of parts, all as will be described more fully hereinafter, illustrated in the drawings, and 60 particularly pointed out in the claims.

In said drawings:

Figure 1 is an elevation of my invention partly in section.

Fig. 2 is a plan view of a plate and its 65 attaching means.

Fig. 3 is a horizontal section on the line 3—3 of Fig. 1; and

Fig. 4 is an elevation of a guard or finder used in connection with my device. 70

Referring now in particular to the accompanying drawings, with special reference to Fig. 1, it will be observed that I have shown my improvement attached to the well-known type of steam generating apparatus, which 75 comprises essentially a boiler 11 having a bottom portion 10 serving as a closure for certain gas heating means, or the like, as is well understood.

Hitherto it has been the practice to attach 80 a gas plate to the top of a boiler through the medium of a plurality of standards or braces, as heretofore pointed out, and in that respect my purpose is similar.

However, I propose to use but a single 85 supporting means for the plate, said means serving in dual capacity in that it likewise acts as a sustaining means for the well-known type of gas burner, which requires but slight alteration for connection to my 90 improved standard. I further propose to couple the gas plate with the standard in a manner to permit compensatory movement thereof under varying thermal conditions, yet effect a fairly rigid connection between 95 the component parts.

To this end the top of said boiler 11 is apertured to receive an internally threaded bushing 13, which in turn is adapted for the reception of the threaded extremity 14 of a 100 standard 23.

As disclosed in Fig. 1, said standard 23 is made more or less ornamental being fluted and flanged to produce a pleasing aspect. This, of course, essentially is immaterial, the 105 important or working parts of said standard comprising the threaded extremity 14, as aforesaid, a circumferential flange 15 and an upwardly directed boss portion 19, at the upper end of said standard, said boss being 110 provided with a threaded central bore 20.

To said standard 23, or more correctly to

the boss 19, is attached a gas plate 21, said gas plate having an annular flange or rim 21^a arranged on its top surface and further having a depending boss portion centrally apertured, as indicated at 20^a, said aperture being counterbored to define a recess 24^a, (see Figs. 1 and 2).

When assembling the parts, the threaded portion 14 of said standard 23 engages the bushing 13 to effect an airtight connection. The plate 21 is now placed upon the boss 19, with their respective apertures alining, whereupon a screw 22 threadedly engaging the threaded aperture of said boss 19 clamps said plate and standard into assembled relation. As observed in Fig. 1, the head of said screw 22 is flat and relatively large in diameter and when in position the top face thereof is slightly below the top surface of said plate and thus no obstruction is met when sad irons or the like are placed on said plate for heating purposes. The relative large diameter of said recess 24^a and the head of said screw 22 prevents lateral displacement of said plate and this construction is indispensable since the screw is not tightly applied to its carrying parts, in order that some latitude of movement of said plate may be provided.

30 The gas burner portion 17 of the device is substantially of standard construction, since it is provided with the usual goose-neck 17^a carrying a fitting 27 in connection with a supply pipe 28, said burner having the usual apertures 25 for the emergence of the flame. However, I propose to provide said burner with a pair of oppositely disposed lugs 16 extending inwardly from the inner periphery thereof, said lugs being suitably apertured 40 for the reception of rivets, bolts or the like, for attaching to the circumferential flange 15, as indicated at 18, in Figs. 1 and 2.

From the foregoing it is apparent that I have devised a single standard for supporting a burner and a gas plate in proper assembled relation, which requires but a slight alteration in the form of the present boiler for its adoption, as distinguished from the plurality of supports and rivets, bolts or the like, in the present structures.

45 After the standard is affixed to the top of the boiler the burner 17 is fitted over the boss 19 and secured to the flange 15, as aforesaid, and then the plate itself may be secured to the boss.

50 While not vitally necessary, I may provide a guard 26 for the burner 17, said guard, (see Fig. 4) having suitable vents to permit the entry of air to the fitting 27, and when

combined with my structure will be positioned as indicated by the dot and dash line 26 in Fig. 1. Its use, of course, protects against accidents by preventing the human hand or clothing coming into contact with the naked frame of the burning gas.

60
65

While the present is a disclosure of the preferred embodiment of the invention, it is to be understood that the invention is not limited thereto, as various changes in the minor details of construction, proportion and arrangement of parts may be resorted to without departing from the spirit of the invention as defined in the appended claims.

70
75
I claim:

1. The combination with a boiler having an apertured top, of a standard threadedly bushed to said apertured top, a boss disposed at the upper end of said standard and having a threaded central bore, said standard having a circumferential flange disposed intermediate its ends, a plate carried by said standard and having a counterbored central aperture, a screw coupling said plate to said standard and a burner presenting inwardly directed lugs connected to said circumferential flange for supporting said burner beneath said plate.

80
85
2. The combination with a boiler having an apertured top, of a standard mounted in said apertured top, a plate connected to the upper end of said standard, a flange intermediate the ends of said standard and a burner supported by said flange and disposed beneath said plate.

90
95
3. The combination with a boiler having an apertured top, of a standard mounted in said apertured top and having a threaded bore arranged in its upper end, a plate carried by said standard and having a central aperture, threaded means for coupling said standard and said plate together, a flange intermediate the ends of said standard and a burner supported by said flange and disposed beneath said plate.

100
105
4. The combination with a boiler having an apertured top, of a standard threadedly bushed to said apertured top, a boss disposed at the upper end of said standard and having a threaded central bore, a plate carried by said standard and having a counterbored central aperture, a headed screw seating into said counterbored central aperture and coupling said plate to said standard, a circumferential flange intermediate the ends of said standard and a burner supported by said flange and disposed beneath said plate.

110
115
In testimony whereof I affix my signature.

NICHOLAS BENENATI.
